UNITED STATES PATENT OFFICE

93,929

DESIGN FOR A WEDDING RING OR SIMILAR ARTICLE

Harry Kousin, New York, and William Sude,
Arverne, N. Y.

Application April 13, 1934, Serial No. 51,392

Term of patent 14 years

To all whom it may concern:

Be it known that we, HARRY KOUSIN, a citizen of the United States and a resident of the city of New York, in the county of Bronx and State of New York, whose post office address is 2084 Honeywell Avenue, Bronx, city of New York, State of New York, and WILLIAM SUDE, a citizen of the United States and a resident of Arverne, Long Island, whose post office address is 178 Beach 68th St., Arverne, Long Island, New York State, have invented a new, original, and ornamental Design for a Wedding Ring or Similar Article, of which the following is a specification, reference being had to the accompanying drawing, forming part thereof.

Figure 1 is a top plan view of the ring, shown in Figure 2, developed on a plane, the characteristic feature of which resides in the combination

of a horseshoe and a heart linked together. The design shows a horseshoe linked to a heart with the base of the heart touching the two ends of the horseshoe. The horseshoe contains a diamond set in the center thereof and the heart is a solid piece of metal.

Figure 2 is a side view of the entire ring.

Figure 3 is a section taken on lines 3—3 shown in Figure 1, looking in the direction of the arrows.

Figure 4 is a section taken on lines 4—4 shown in Figure 1, looking in the direction of the arrows.

Figure 5 is a perspective view thereof.

We claim:

The ornamental design for a wedding ring or similar article as shown and described.

HARRY KOUSIN.
WILLIAM SUDE.
